UNITED STATES PATENT OFFICE.

PAUL KAMINSKI, OF BERLIN-PANKOW, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

TELEADJUSTER FOR GUNS AND THE LIKE.

Application filed November 16, 1922. Serial No. 601,422.

To all whom it may concern:

Be it known that I, PAUL KAMINSKI, a citizen of the German Empire, residing at Berlin-Pankow, Germany, have invented 5 certain new and useful Improvements in a Teleadjuster for Guns and the like, of which the following is a specification.

Heretofore, arrangements have become known, which allow a control of guns or 10 the like, as to their elevation as well as to their lateral direction, from one direction telescope, without the adjustment in the horizontal plane being of any influence on the elevation.

15 The present invention has for its object to provide a particularly appropriate construction of such an arrangement, which allows the use of the same electric transmitters for the search-lights, range meters and 20 telescopes controlled by the direction telescope and which are adjusted parallel to the latter, as for the control of the guns, which besides must receive the angle of elevation.

25 For this purpose, according to the present invention, the non-stationary transmitters of the arrangement, which move with the direction telescope and which transmit the parallel position to the direction telescope, 30 are made to adjust separate stationary electric auxiliary receivers.

35 The adjustment of the following pointers, following the position of the pointers of the auxiliary receivers is then added, in a way known in the art, to the movement of the range adjuster of the stationary transmitters controlling the guns.

40 The accompanying drawing shows, diagrammatically, a perspective view of the improved arrangement.

The direction telescope F is, in a way known in the art, adjustable in a perpendicular plane on its pivot a by means of a crank k, worm e and toothed sector d, 45 while the bracket h carrying the pivot a of the direction telescope F can be slewed together with the latter, in a horizontal plane —by means of a crank b, said latter adjustment being transmitted, in a way known in the art, over a gearing y to the electric transmitters S for the horizontal direction, and the required correction for the concentration correction being added to said transmitters from the drum T₁ over the inter-

mediary gearing r₂, r₁, r₃, r₄, f, r₅, r₆, n, 55 and p₇. The concentration correction has, as known, the value $\frac{A}{E} \sin \alpha$: E designating the range, A the horizontal distance between gun and direction telescope, and α 60 the lateral direction angle. In the gearing above-mentioned, the automatic transmission to the planet wheel p₇ is effected: for the value A through the transmission gearing A, of the sine for the lateral adjustment 65 through the sine line K, and for the value of the range through the adjustment of the drum T₁.

The tele-control of the elevation of the guns, according to the invention, takes place 70 as follows:—

The crank k turns over intermediary gearings i, l, p₃, p₂ electric transmitters g₁, g₂ for coarse and fine adjustment, which are mounted on the revolvable bracket h. The 75 training of the direction telescope F in a horizontal plane becomes thereby independent from the movement in a perpendicular plane, so that the usual mechanical bevel gearings, which hitherto were to ensure said 80 independence, are omitted. Said non-stationary transmitters g₁, g₂ which thus participate in the horizontal training of the direction telescope, act, in one of the known ways: for instance the known alternating 85 current systems, either directly on the receivers of search-lights or the like, which do not require a ballistic elevation angle, or on stationary auxiliary receivers x₁, x₂ for the guns, which must receive the ballistic 90 elevation angles as an addition.

On said receivers x₁, x₂, following pointers z₁, z₂ are adjusted in a way known in the art, and said adjustment is transmitted to the transmitters g₃, g₄ for the guns over 95 the gearing m, u, q, v, p₄ and planet wheel p₅. To said transmitters, the ballistic elevation angle is added from the adjustable drum T₂ through the planet wheel p₅ and and the gearing p₆, t, o. 100

If the direction telescope F is situated above the guns, for instance in the top of a man-of-war, said elevation must be considered for firing. The value of said elevation, the so-called angle of dip, is 105

$H = \frac{H}{E}$: E designating the range and H the perpendicular distance between gun and

direction telescope. As the drum T_1 on the bracket h adjusts already the range, and the value H is constant, the correction H can be directly transmitted to the transmitter g_1, g_2 , for which purpose the range value of the drum T_1 is made to act as an addition on the planet wheel p_2 through an intermediary gearing r_1, r_3, r_4 , 10 e, w_2, w_1, p_1 while the constant value H is arranged in the transmission ratio, for instance of the wheels w_1, w_2 .

It is immaterial for the scope of the invention whether the adjustment of the drums T_1 and T_2 takes place by hand or by a clockwork or the like, and whether the transmission at the auxiliary receivers x_1 and x_2 takes place on the follow-the-pointer principle or by any hunting principle.

What I claim, is:—

1. In an arrangement for the telecontrol of guns or the like, a direction telescope and stationary transmitters for transmitting the training movements of the telescope with respect to the concentration correction, and non-stationary transmitters for transmitting the vertical movements of said telescope to the guns, said direction telescope being located higher than the guns, a drum calibrated for the range, and suitably connected and operated to impart the concentration correction to the stationary transmitters for the bearing angle, and special

gearing for connecting said drum also to said non-stationary transmitters for the vertical movements of said telescope, said special gearing having a suitable ratio for correcting the angle of dip. 35

2. In an arrangement for the telecontrol of guns or the like, a direction telescope and stationary transmitters for transmitting the training movements of the telescope with respect to the concentration correction, and non-stationary transmitters for transmitting vertical movements of said telescope to the guns, said direction telescope being located higher than the guns, a drum calibrated for the range and suitably connected and operated to impart the concentration correction to the stationary transmitters for the bearing angle and special gearing for connecting said drum also to said non-stationary transmitters for the vertical movements of said 40 telescope, said special gearing having a suitable ratio for correcting the angle of dip, and stationary auxiliary receivers adapted to be acted upon by said non-stationary transmitters, and being mechanically connected to said stationary transmitters which control the setting of the guns and means for adding the angle of elevation to the adjustment of said stationary transmitters. 45 50 55 60 65

In testimony wherof I affix my signature.

PAUL KAMINSKI.
